UNITED STATES PATENT OFFICE

2,033,666

VALVE OPERATING DEVICE

Roy H. Zinkil, Oak Park, Ill., assignor to Crane
Co., Chicago, Ill., a corporation of Illinois

Application July 20, 1934, Serial No. 736,234

7 Claims. (Cl. 4—64)

This invention relates more particularly to improvements in a closet bowl seat device having for its principal object a new and improved means for actuating a flush valve in connection with the flushing of the bowl.

One of the important objects of this invention is the provision for a flush valve operating mechanism in which no inherently flexible parts are employed, thus eliminating the objections usually traceable to the latter, such as the necessity for providing proper clearances in the allowance for wear, stretch, slippage and the like.

Another important object is to provide a construction which omits the use of closely fitting links or bearings in connection with the operating levers, and thus reducing the number of operating parts subject to wear to a minimum.

Another important object is to provide a construction in which a substantially frictionless bearing or contact is made with the lever actuating means.

Another important object is to provide for a positive contact, as distinguished from a rigid connection between the member to be actuated and the hinged fork and by means of which valve actuation is obtained.

Other objects and advantages will become apparent upon reading the specification, in which

Fig. 1 is a plan view of one form of my device embodying the invention.

Fig. 2 is a partial sectional view showing the method of providing the actuating contact between the closet seat and the flush valve.

Like numerals refer to like parts throughout the figures.

Referring now to the drawing, I have illustrated a device consisting in combination of a closet bowl 1, with a seat 2 having a hinged connection therewith, the latter consisting of a bracket 3 having journalled projections 4 with a shaft 5 extending across and between the said projections. The seat is thus hingedly pivoted about the said shaft as an axis. Any convenient means for limiting the upward movement of the seat is provided which in this case consists of the stop 6, which in its maximum upward movement abuts against the surface 7. The ends of the shaft 5 are journalled within the end pieces 10, the latter being attached to the bowl by means of the threaded studs and nuts 10a and 10b, respectively.

Extending preferably integrally as a part of the bracket 4 is a centerpiece 8, which is bored out as at 9 to serve as a bearing for the extension fork shaft or lever 11, the latter fitting closely within

55 the bearing 9 and is held against axial movement

by means of the set screw 12, preferably threaded to hold the shaft securely within the said bearing. As shown in Fig. 1, between the part 8 and the projections of the bracket 4 the spacing pieces or sleeves 13 are provided. The fork lever 11 is extended to the flush valve 14 with the flush valve, as indicated, being conveniently attached to the bowl so as to flush it.

The flush valve is of the type known as the non-hold open and which operates to flush the bowl 10 by tilting the actuating stem 15 of the valve to one side. When the actuating stem is thus moved, the valve and stem are lifted by the water since the actuating stem consists of two parts or members, a member 15 as previously mentioned 15 and a sliding member 16—the more detailed information of the valve being had by referring to U. S. Patent No. 1,114,398 dated October 20, 1914.

When the parts are connected in position as shown in Fig. 2, the closet seat is held in a partially lifted position by means of the spring 17, and when the seat is depressed, the forked head 18 engages the underside of the button 19 of the horizontally extending member 21 thus pulling it forward against the action of the spring 17 so 25 as to permit the flush valve stem 15 in effect to project past the end 22 of the horizontal actuating member 21. When the seat 2 is released, the horizontal actuating member 21 because of the spring 17 is drawn back to its normal position as 30 indicated in the drawing. However, since the flush valve stem 15 had dropped down past the end 22 of the horizontal member 21 it is apparent that when the member 21 returns to its normal position, it will strike the side of the stem 15, tilt- 35 ing the latter sideways so as to tip the valve disc (not shown) of the flush valve 14 which actuates the flush valve, and thus causing the valve stem 15 and the sleeve 16 to be lifted. This operation causes the bowl to be flushed. With the rising 40 of the parts 15 and 16, the horizontal actuating lever 21 moves further inwardly so as to again locate itself under the end of the stem 15. Thus, when the main valve (not shown) seats again as described in the aforementioned patent, the stem 45 15 comes to rest upon the extension 22 of the horizontal actuating lever 21. It is, therefore, apparent that the bowl is actually flushed, not when the closet seat is depressed, but when it is returned to its normally tilted position, as shown in Fig. 2. 50 It is further evident that the spring 17 which controls the flush valve horizontal actuating lever 21 also lifts the seat to its normal or lifted position above the rim 23 of the bowl 1.

In order to properly adjust the amount of 55

movement by the seat 2 necessary in actuating the reciprocating member 21, a set screw 20 is threadedly connected to the supporting member 8 into which the fork member 11 is held and is locked in its position by a locknut 20a. That is, set screw 20 governs the angle of inclination of the seat 2 and in so doing, directly controls the amount of travel of the seat from its partly raised position to the fully depressed position, which in turn governs the horizontal movement of the reciprocating member 21.

It is also apparent that the forked contact with the button head 19 provides for the exertion of a force on the underside of the button head in one direction only and thus permits the spring likewise to control in a positive bearing in one direction only. Therefore, wear occurring between the underside of the button head and of the bearing surface of the fork is reduced to a minimum. Similarly the operating effort required is reduced accordingly. The button head 19, may be made integral with the operating member 21 or it may be threadedly attached thereto. Likewise, the operating lever 21 may be made in two or more sections so as to permit of convenient extensions in order to suit the various installations. This is also applicable to the forked extension 11, permitting it to be lengthened or shortened to suit the various heights at which the flush valve may be installed above the bowl.

From the foregoing it is apparent that numerous modifications may be made incorporating the spirit of my invention and I, therefore, desire to be limited only to the extent of the claims appended hereto.

I claim:

1. A closet flushing device comprising in combination a closet, a closet seat, a flush valve installed for actuation by said seat, a closure member within said valve, a stem actuating said closure member, the said stem comprising an end portion telescoping within a part intermediate thereof, a reciprocating member transversely positioned with relation to said stem for actuating the latter, a substantially vertical member superposed above said closet having at one end bifurcated means for engagement with said reciprocating member, a pivotal support for the said seat provided with independent means for the adjustment of the said vertical member and of the said reciprocating member.

2. A closet flushing device comprising in combination a closet, a closet seat, a pivotal support therefor, a flush valve installed for actuation by said seat, a closure member, a telescopically movable compound stem for actuating said closure member, a reciprocating member for actuating said flush valve, a resilient member mounted upon said reciprocating member, a housing for said resilient member, adjustable means upon said pivotal support for controlling the horizontal movement of said reciprocating member in one direction, a substantially vertical member mounted upon said pivotal support and having a bifurcated end for engagement with said reciprocating member, the said seat being normally inclined slightly with respect to said closet, whereby upon the depression of the said seat the said reciprocating member is moved against said resilient member sufficiently to allow said stem to move transversely across the inner end of said reciprocating member, valve actuation occurring upon release of the said seat.

3. A closet flushing device, comprising in combination a closet, a closet seat, a flush valve in-

stalled for actuation by said seat, a closure member within said valve, a stem actuating said closure member, a reciprocating member transversely positioned with relation to the said stem for actuating the latter, the said stem normally resting upon said reciprocating member and having a movable extension projecting beyond the end thereof upon transverse movement of the said reciprocating member, a substantially vertical member pivotally positioned upon said closet and having at one end bifurcated means for engagement with said reciprocating member, a pivotal support for the said seat provided with independent means for adjustment of the said vertical member and of the reciprocating member.

4. A closet flushing device, comprising in combination a closet, a closet seat, a flush valve installed for actuation by said seat, a closure member within said valve, a stem actuating said closure member, a reciprocating member transversely positioned with relation to the said stem for actuating the latter, the said stem having an axially movable extension enabling the latter to extend beyond the end of the said reciprocating member upon transverse movement of the said latter member, a substantially vertical axially adjustable member pivotally positioned upon said closet and having at one end bifurcated means for engagement with said reciprocating member, a pivotal support for the said seat provided with independent means for adjustment of the said vertical member and of the reciprocating member.

5. A closet flushing device, comprising in combination a closet, a closet seat, a flush valve installed for actuation by said seat, a closure member within said valve, a stem actuating said closure member, an axially adjustable reciprocating member transversely positioned with relation to the said stem for actuating the latter, the said stem normally supported by said reciprocating member and having a relatively movable extension enabling the latter to extend beyond the end thereof upon transverse movement of the said reciprocating member, a substantially vertical member pivotally positioned upon said closet and having at one end bifurcated means for engagement with the said reciprocating member, a pivotal support for the said seat provided with independent means for adjustment of the said vertical member and of the reciprocating member.

6. A closet flushing device, comprising in combination a closet, a closet seat, a flush valve installed for actuation by said seat, a closure member within said valve, a stem actuating said closure member, a reciprocating member transversely positioned with relation to the said stem for actuating the latter, the said stem having a movable extension enabling the latter to extend transversely beyond the end of the said reciprocating member upon movement of the latter, a substantially vertical member pivotally positioned upon said closet and having at one end bifurcated means for a line bearing engagement with the said reciprocating member, a pivotal support for the said seat provided with independent means for adjustment of the said vertical member and of the reciprocating member.

7. A closet flushing device, comprising in combination a closet, a closet seat, a flush valve installed for actuation by said seat, a closure member within said valve, a stem actuating said closure member, a reciprocating member transversely positioned with relation to the said stem

for actuating the latter, the said stem having extendible means enabling the latter to project transversely beyond the end of the said reciprocating member upon movement of the latter, a substantially vertical member pivotally positioned upon said closet and having at one end means

operatively engaging the said reciprocating member, a pivotal support for the said seat provided with independent means for adjustment of the said vertical member and the said reciprocating member.

ROY H. ZINKIL.
